END PIECE FOR A MULTI-STRAND NECKLACE

William A. Mancini, Warwick, R.I., assignor to Lorac Company, Inc., Providence, R.I., a corporation of Rhode Island

Filed Nov. 9, 1959, Ser. No. 58,287

Term of patent 3½ years

(Cl. D45—1)

Fig. 1

Fig. 2

Fig. 3

Fig. 4

Fig. 5

Fig. 1 is a front elevational view of an end piece for a multi-strand necklace, showing my new design;

Fig. 2 is a rear elevational view thereof;

Fig. 3 is a top plan view thereof;

Fig. 4 is a bottom plan view thereof;

Fig. 5 is a side elevational view thereof.

I claim:

The ornamental design for an end piece for a multi-strand necklace, substantially as shown.
